(57) **CLAIM**

The ornamental design for an outer jacket for a testing device, as shown and described.

DESCRIPTION

FIG. 1 is an upper front right perspective view of an outer jacket for a testing device showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is an upper front right perspective view thereof shown in use with a testing device for illustration of environment; FIG. 9 is an upper front right perspective view of an alternative embodiment of the outer jacket for a testing device shown in FIG. 1;

FIG. 10 is a front elevation view thereof;

FIG. 11 is a rear elevation view thereof;

FIG. 12 is a top plan view thereof;

FIG. 13 is a bottom plan view thereof;

FIG. 14 is a left side elevation view thereof;

FIG. 15 is a right side elevation view thereof; and,

FIG. 16 is an upper front right perspective view thereof shown in use with a testing device for illustration of environment. The broken lines shown in the figures illustrate environmental subject matter and form no part of the claimed design.
